UNITED STATES PATENT OFFICE

NATHANIEL E. LOOMIS, OF WESTFIELD, NEW JERSEY, ASSIGNOR TO STANDARD OIL DEVELOPMENT COMPANY, A CORPORATION OF DELAWARE

METHOD OF TREATING OILS WITH FINELY-DIVIDED SOLID MATERIAL

Application filed June 12, 1928. Serial No. 284,850.

This invention relates to the treatment of oils with finely divided solid materials, such as decolorizing clay. The invention will be understood from the following description 5 read in conjunction with the drawing which is a side elevation, with parts in section, of apparatus in which my method may be carried into effect.

A still 1 is mounted in any suitable setting 10 2, heated by means of a burner 3. A vapor duct 4 communicates with a rectifying column 5. This is provided with the customary transverse partitions 6, which in turn carry overflow pipes 7 and vapor distributors (bell 15 caps) 8. A cooling coil 9 is provided in the upper part of the column. Vapors leave the rectifying column through a pipe 10, discharging into a condenser 11. Oil may be introduced to the system through a pipe 12.

20 A clay hopper 13 communicates with a clay feeder 14, which is adapted to supply clay in a continuous and uniform manner to material flowing in pipe 12. A pump 15 is connected to pipe 12 and discharges through a 25 pipe 16 into a heat exchanger 17, which may consist of any suitable device for passing liquid received from pipe 16 into indirect heat exchanging relationship with another liquid, thereafter delivering the partly heated liquid 30 into a pipe 18 which in turn discharges into rectifying column 5, at or near its mid-portion.

A pipe 19 is connected near the base of column 5 and communicates with branches 20 35 and 21, controlled by valves 22 and 23 respectively, whereby material may be conducted through or around heat exchanger 17 and delivered into a pipe 24. Pipe 24 communicates with a filter 25, which may be of any 40 suitable type adapted to separate finely divided solids, suspended in an oil medium. Filtrate may be discharged from the filter through pipes 26 and 27, discharging into a receiver 28.

45 A pipe 29 communicates with this receiver near the base and discharges into the suction side of a pump 30, which is adapted to force liquid into a pipe 31, communicating either with a heat exchanger 32 or a by-pass 33, controlled by valves 34 and 35 respectively. Both

heat exchanger 32 and by-pass 33 communicate with a pipe 36, which discharges into still 1. A draw-off pipe 37 leads from the base of the still into heat exchanger 32 and the liquid delivered by pipe 37 after passing 55 through this exchanger may be thereafter withdrawn from the system through a pipe 38.

A preferred method of operating the described apparatus is substantially as follows:

The oil which is to be treated, for example a crude petroleum oil, is supplied through pipe 12. The method is particularly adapted for the treatment of paraffin or semi-paraffin base crudes, which are to be decolorized preparatory to the manufacture of petrolatum and/or cylinder stock. By proper control of the clay feeder 14, I add a portion of fine clay to the crude oil. This clay is preferably ground to a fineness of at least 50% through 65 200 mesh and may, if desired, be preliminarily treated with acid to increase its activity. It is one of the advantages of my process that a preliminary drying of this clay is not essential and the clay may therefore be added 70 to the oil in a moist condition or even in the form of a suspension of clay in oil or water.

The amount of clay to be added to the oil may vary over wide limits, thus for example, I may add from .1 up to 10% by weight of the 80 oil, although I preferably add about 2½%. The mixture of clay and oil is delivered by pump 15 through heat exchanger 17 into rectifying column 5. A body of oil is maintained in still 1 and vapors therefrom are 85 rectified in column 5. The lighter portions of the crude oil are vaporized and rectified in the column and the rectified vapors pass off through pipe 10 to be condensed in 11, from which they are diverted to any suitable accumulator.

The bottoms from column 5 containing clay in suspension, are conducted away through pipe 19 and preferably passed 95 through exchanger 17 in indirect heat exchanging relationship to the mixture of clay and feed oil. After being partly cooled in this manner, the bottoms are separated from the suspended clay in filter 25. The filtrate collects in receptacle 28 and is thereafter

forced by pump 30 through pipe 31 into still 1. This filtrate is preferably passed in heat exchanging relationship to liquid which is continuously withdrawn from the still 5 through pipe 37. The withdrawn liquid, after being partly cooled in this manner, is diverted through pipe 38 to any suitable accumulator.

The amount of heating which takes place 10 in still 1 is so regulated as to drive overhead through vapor pipe 10 a first distillate, such as gasoline, or if the oil has been previously topped, kerosene. The amount of cooling accomplished by coil 9 in the upper 15 part of column 5 is correspondingly regulated to give the desired sharpness of separation and to control the final boiling point of the overhead vapor passing off through 10.

Without any extra equipment or additional 20 control, the decolorization, dehydration, and rectification of the crude oil may be simultaneously accomplished. It will, of course, be apparent that the crude oil may receive a preliminary acid treatment if desired, and that 25 the recovered clay may be regenerated and re-employed in the system.

The foregoing specific description of apparatus and method of operation is for purpose of illustration and it is my intention 30 that the invention be limited only by the appended claims or their equivalents, in which I have endeavored to claim broadly all inherent novelty.

I claim:

35 1. The method of treating crude oil, with or without a preliminary topping, which comprises introducing a mixture of crude oil and clay into the mid-portion of a group of rectifying zones, withdrawing liquid bottoms 40 containing suspended decolorizing clay from the said group of rectifying zones, filtering said liquid bottoms to separate clay therefrom, conducting the filtered bottoms into a body of oil maintained at a temperature at 45 which hydrocarbon vapors are evolved and conducting the evolved vapors into the said group of rectifying zones at or near the lower portion thereof.

2. Method according to claim 1, in which 50 the said body is heated to the extent necessary to cause rectification to take place in the said group of rectifying zones and the formation of a rectified vapor consisting substantially of gasoline.

55 3. Method according to claim 1, in which the added clay contains substantial quantities of moisture.

4. Method according to claim 1, in which the crude oil has been preliminarily treated 60 with sulfuric acid.

NATHANIEL E. LOOMIS.
